(57) **CLAIM**

The ornamental design for the valve handle, as shown and described.

DESCRIPTION

FIG. 1 is a front perspective view of a valve handle according to the present disclosure;

FIG. 2 is a rear perspective view of the valve handle of FIG. 1; FIG. 3 is a front view of the valve handle of FIG. 1;

FIG. 4 is a back view of the valve handle of FIG. 1;

FIG. 5 is a first side view of the valve handle of FIG. 1, the opposite side being a mirror image thereof;

FIG. 6 is a first end view of the valve handle of FIG. 1; and, FIG. 7 is a second, opposite end view of the valve handle of FIG. 1.

The broken lines in the drawings illustrating environmental structure or boundaries that form no part of the claimed design.

1 Claim, 3 Drawing Sheets

FIG. 3

FIG. 4

FIG. 5**FIG. 6****FIG. 7**
